SHIRT CASE

Neal I. Paulsen, St. Louis Park, Minn.

Application December 15, 1941, Serial No. 422,989

5 Claims. (Cl. 206—7)

My invention relates to improvements in packaging and, more particularly, to a case for holding an individual shirt.

One of the objects of this invention is to provide a self-contained case for holding a folded individual shirt having an attached collar.

Another object of the invention is to provide a self-contained shirt case foldable from a single sheet of material.

Still another object of this invention is to provide a self-contained case for holding a folded individual shirt having an attached collar, said case having means for holding and supporting the collar thereof.

Other objects of the invention will be apparent from the following description, reference being had to the accompanying drawings.

To the above end, generally stated, the invention consists of the novel construction and arrangement of parts hereinafter described and defined in the claims.

In the accompanying drawings, which illustrate the invention, like characters indicate like parts throughout the several views.

Referring to the drawings:

Fig. 1 is a top plan view of the improved shirt case having a shirt provided with an attached collar folded therein;

Fig. 2 is a back plan view of the same;

Fig. 3 is a side elevation of the improved shirt case and also showing a second shirt case turned end for end, upside down and placed on the first noted shirt case to illustrate the method of stacking the improved shirt cases;

Fig. 4 is an upper end view of the improved shirt case;

Fig. 5 is a lower end view of the same;

Fig. 6 is a view partly in elevation and partly in longitudinal central section taken on the line 6—6 of Fig. 1, on an enlarged scale;

Fig. 7 is a view corresponding to Fig. 1, with the exception that some parts are broken away and sectioned, in part, to expose the shirt in the case;

Fig. 8 is a view partly in elevation and partly in transverse vertical section taken on the line 8—8 of Fig. 1, some parts being shown in different positions by means of broken lines;

Fig. 9 is a view partly in elevation and partly in transverse vertical section taken on the line 9—9 of Fig. 1;

Fig. 10 is a fragmentary view in horizontal section taken on the line 10—10 of Fig. 4;

Fig. 11 is a fragmentary perspective view of the upper right-hand corner portion of the improved

shirt case and showing the respective corner-forming accordion plait partly open;

Fig. 12 is a plan view, on a reduced scale, of the sheet of cardboard or similar material as the same comes from a die and which sheet, when folded on the scores indicated by broken lines, forms the improved shirt case;

Fig. 13 is a fragmentary top plan view showing a modification of the improved shirt case; and

Fig. 14 is a fragmentary detail view in section taken on the line 14—14 of Fig. 13, on an enlarged scale.

My improved shirt case is formed from a single sheet A of cardboard or a similar foldable material of sufficient thickness and strength to give the shirt case the required rigidity to withstand ordinary rough handling while being delivered from a laundry to a customer, or from manufacturer to user.

The sheet A, as shown, is square and a line extending diagonally of the sheet between two of its corners is at the transverse center of the shirt case and a line connecting the other two corners of the sheet A is at the longitudinal center of said sheet.

To assist in forming the two upper corners of the shirt case, the longitudinal edge portions of the sheet A, diverging from the upper corner of said sheet, are intermediately cut to form two notches B; and to assist in forming the two lower corners of the shirt case, the longitudinal edge portions of the sheet A, diverging from the lower corner of the said sheet, are intermediately cut to form two notches C.

The sheet A is scored and the shirt-forming sections thereof, in part, are identified as follows: two outer scores D, two inner scores E, that extend longitudinally between the notches B and C; two upper scores F and G and two lower scores H and I that extend transversely between the notches B and C, respectively. Scores F and G are parallel and the latter score is spaced outwardly of the former score. The lower edge portions of the notches B are aligned with the score F and the upper ends of said notches are at the ends of the score G.

The sheet A is further provided with two scores J that extend from the ends of the score G to the score F inwardly of its ends and are in converging relation from the score G. Scores D converge slightly from the intermediate corners of the notches B to the upper edge portions of the notches C and are spaced slightly outwardly of the intermediate corners of the notches C.

The upper end member 15 of the shirt case is

formed by folding the sheet A on the scores F, G and J. V-shaped section of the sheet A outwardly of the score G, when folded inwardly on the score G, affords a collar-supporting wing 16 that underlies the top member of the shirt case. The upper edge portion of the notches C are aligned with the score H; the score I is parallel to the score H and spaced outwardly therefrom. The lower end member 17 is formed by folding the sheet A inwardly on the scores H and I. It will be noted that the distance between the ends of the scores D and E at the notches C is the same as the width of the lower end member 17.

The top member 18 of the shirt case is formed by folding the sheet A downwardly on the scores E—E, and the side members 19 of said case are formed by further folding the sheet A inwardly on the scores D. V-shaped sections of the sheet A outwardly of the scores D, when said sheet is folded to form the side members 19, afford bottom wings 20 that extend in opposite directions under the shirt case in overlapping relation. When the sheet A is folded to form the end member 17, the V-shaped section of said sheet, outwardly of the score I, affords a further bottom wing 21 that is overlapped at its edge portions by the bottom wings 20.

It will be noted that the lower end member 17 is very narrow, in respect to the upper end member 16, and that the top member 18 slopes upwardly from said lower member. The purpose of this is to give the shirt case additional depth at its upper end portion for the collar of the shirt in the case. In some instances, it might be desirable to fold the sheet A only on the score H so that the width of the lower end member of the shirt case is very narrow. The side members 19 slope inwardly and upwardly and the width of the top member 18 at its upper end portion is substantially the same as the transverse width of the collar of the shirt and the inclined side 19 holds the shirt collar against lateral shifting movement in the shirt case.

The V-shaped sections of the sheet A between the scores F and J are intermediately scored at K and afford accordion plaits 22 that connect the upper end member 15 at its end to the side members 19, at their upper ends.

When the sheet A is folded to form the shirt case, the accordion plaits 22 extend into the shirt case and lie against the sloping sides thereof. It will be noted, by reference to Fig. 12, that the upper wings of the accordion plaits 22 are somewhat narrower than the lower wings thereof, so that when said plaits are folded into the shirt case, they will draw the upper end member 15 inwardly between the side members 19 so that said side members rest on the ends of the end member 15 and afford a box structure that reinforces the shirt case to withstand side pressure.

The bottom wings 20, when folded, are separably connected, as shown by a lock comprising a transverse slot 23 in one of said wings through which the end portion of the other of said wings is inserted, and a notch 24 in the last noted wing into which the wing having the slot 23 extends.

The shirt X having an attached collar Y, as the same comes from the ironer, is folded on a folding board, not shown, in the customary manner in which the sleeves thereof, are folded onto the back of the shirt with the cuffs under the collar Y. The body portion of the shirt is then folded longitudinally, at the edges of the bosom, inwardly upon the back of the shirt and the one

upon the other. Next, the tail portion of the shirt is folded inwardly upon the body of the shirt. Said shirt is again folded inwardly upon itself to bring its folded tail portion into an intermediate position within the folded shirt.

The shirt case is applied around the shirt X by and during the process of folding the sheet A to form said case. In applying the shirt case around the shirt X, the sheet A is turned upside down and the folded shirt is also turned upside down and placed on said sheet with its bosom and collar resting on the inner surface of the top member 18. The steps of folding the sheet A are substantially as follows: First, the accordion plaits are folded and the sheet A folded on the score F to bring said plaits into the shirt case and the end member 15 and the collar support 16 into an upright position. Next the collar support 16 is folded inwardly on the score G and over the collar Y at the back thereof and under the cuffs of the shirt X. The sheet A is then folded on the score H to bring the end member 17 and the bottom wing 21 into upright positions. It may be here stated that at the time the end member 15 and the plaits 22 are folded into operative positions, the sheet A is also folded on the scores E—E to bring the side members 20 into operative positions in which they extend upwardly and outwardly. Next, the sheet A is folded on the score H to bring the end member 17 and the bottom wing 21 into upright positions and thereafter said wing is folded on the score I inwardly onto the folded shirt X. The bottom wing 20, having the lock slot 23, is next folded on the respective score D, inwardly onto the folded shirt X and thereafter the other bottom wing 20 is folded on the respective score D inwardly onto said shirt and the first noted bottom wing 20 and its free end portion inserted through the lock slot 23 and its notch 24 interlocked with said first noted bottom wing 20.

The member 16 affords a support on which the collar Y at its back portion rests and the end member 15 affords a support for the top member 18 and holds the same above the collar Y and thus prevents said collar from being crushed or wrinkled by pressure applied on said top member.

Obviously, the bottom wing 21 is held in operative position by the overlapping bottom wings 20 and in place of the lock 23—24, the overlapped wings 20 may be connected in any other suitable manner, for instance, by means of a gummed label or a piece of gummed tape.

When the laundry has more than one shirt for a customer, the shirt cases, each of which contains a single shirt, may be stacked, as shown in Fig. 3, and tied in a bundle by a piece of string or gummed tape or wrapper passed therearound.

To further reinforce the shirt case and thereby afford further protection to its collar Y, a support 25 is cut and pressed from the top member 18 at the transverse center thereof. This support 25, as the same appears before being pressed from the member 18, has a wide free end and the sides thereof are in converging relation toward the point of attachment of said support with the top member 18 and at which point said support is relatively narrow. The top member 18 is scored at L, between the sides of the support 25 at the attached end thereof, and its free end and the score L extend parallel to the score F. A single score M extends transversely across the support 25 at its longitudinal center and two

parallel scores N extend longitudinally across the support 25 from the ends of the score L.

The support 25 remains in its original position in which it lies in the plane of the top member 25 until the shirt case is secured around the shirt therein, and said case turned right side up. To fold the support 25 into an operative position, the same is first lifted out of the opening formed in the top member 18 by cutting said support therefrom, by a hinge-like movement on the score L, as shown by broken lines in Fig. 8. The opening in the top member 18, formed by cutting and lifting the support 25 therefrom, affords a sight opening 26, for a purpose which will presently appear. With the support 25 in an upright position, as shown in Fig. 8, its free end portion is folded on the score M downwardly toward the sight opening 26 and onto the respective side of the attached portion of said support. This folding of the support 25 upon itself affords a two-ply reinforced structure. Next, the side portions of the support 25 are folded on the scores N away from the sight opening 26 and then the support 25 is moved with a hinge-like movement on the score M through the sight opening 26 and into an upright position in the shirt case close to the collar band on the inside and at front thereof. The support 25, when in an operative position, rests at its folded lower end, on the back of the shirt within the collar band. When the support 25 is released, after being placed in an operative position within the shirt case, its free side portions will spring toward the collar band and closely follow the contour thereof. The support 25 holds the top member 18 out of contact with the collar Y and thereby protects said collar from pressure applied on the top member 18 from the outside of the shirt case.

Referring again to the sight opening 26, it is well known that shirts, upon delivery to a laundry, are given an identifying mark as to the owner, and this mark is placed on the back of the collar band on the inside thereof. Shirts, after being laundered, are folded and usually wrapped before sorted as to ownership and the wrapping must be such that the identifying mark on the collar band is visible. In the use of my improved shirt case, a laundered shirt is first folded and then the shirt case folded therearound and secured as heretofore described. With a shirt thus wrapped in my improved shirt case, the identifying mark thereon is clearly visible through the sight opening 26.

To further protect the shirt collar Y so that it will retain its shape as the same comes from the ironer, a plain band 27 of the same material as the shirt case or any other suitable material is placed between the shirt band and the support 25 and extends around said band on each side of the support 25, see Fig. 6.

To still further protect the shirt collar Y the same, at its lapels, is held suspended by a collar support 28 cut and pressed from the top member 18 just below the sight opening 26. This collar support 28 has substantially the same outline as the support 25 except that it is smaller in size, extends in the opposite direction therefrom and its attached end is relatively close to the attached end of the support 25. The attached end of the collar support 28 is scored parallel to the score L, as indicated at O, and said support is further scored in two places, as indicated at P. The scores P extend from the ends of the score O longitudinally of said support to the free end thereof and are in converging relation from said score O.

The wings or side portions of the support 28 are inserted under the lapels of the shirt collar Y by first folding the same inwardly on the scores P to contract the normal width thereof sufficiently to go between said lapels and then the support 28 is folded downwardly on the score O until the wings of the support 28 are below the lapels of the collar Y. Upon releasing the collar support 28, when positioned as above described, its wings will spring into their original position and thereby be projected under the lapels of the collar Y. The support 28 will also spring upwardly toward its original position and thereby cause the wings to produce a lifting action on the lapels of the collar Y and thus hold the same suspended in the shirt case.

From the above description, it is evident that the improved shirt case, which holds a folded individual shirt having an attached collar, protects the same against soiling and wrinkling and the collar thereof is protected and supported in a manner in which it will retain its shape as the same comes from the ironer. One of the many advantages of my improved shirt case is that a shirt may be kept therein up to the time it is to be worn and the wearer thereof may readily see the style and color thereof through the sight opening 26 before the shirt is removed from the case. The improved shirt case also affords a convenient package for a shirt when carrying the same in a bag, suitcase, trunk or the like.

Referring now to the modification of my improved shirt case, as shown in Figs. 13 and 14, the parts thereof that correspond to like parts shown in Figs. 1 to 12 inclusive, are given like reference characters followed by a prime ('). The structure disclosed in Figs. 13 and 14 is identical with the structure disclosed in Figs. 1 to 12, inclusive, with the exception of the added collar supports 29 that are cut and pressed from the top member 18' at the sides of the sight opening 26'. These collar supports 29 extend downwardly in the shirt case within the collar band and engage said band and support the collar.

The drawings illustrate a commercial form of the invention, but it will be understood that the same is capable of certain modifications as to details of construction, arrangement and combinations of parts within the scope of the invention herein disclosed.

The word "cardboard" is herein used in a broad sense to cover any suitable foldable material. Also the word "score" is used in a broad sense to cover any means for weakening the sheet on a given line to facilitate the folding thereof.

What I claim is:

1. A case for holding therein a shirt having an attached collar and folded with its back underlying the opening formed by the band of the collar, said case having a top member, and an attached support cut and pressed from the top member overlying the collar band opening, said support being folded into the case in an upright position at the front of the collar band, said support resting on the back of the shirt and supporting the top member therefrom to prevent the collar from being crushed by pressure tending to flatten the case.

2. A case for holding therein a shirt having an attached collar and folded with its back underlying the opening formed by the band of the collar, said case having a top member, and a support cut and pressed from the top member overlying the collar band opening, said support having a relatively narrow neck portion attached to the

top member, said support and its neck portion being folded into the case in an upright position, said support also being folded between its neck portion and the collar band at the front thereof, said support resting on the back of the shirt and supporting the top member therefrom to prevent the shirt from being crushed by pressure tending to flatten the case.

3. A case for holding therein a shirt having an attached collar and folded with its back underlying the opening formed by the band of the collar, said case having a top member, a main supporting band within the collar band opening, engaging the collar band at the front thereof, and resting on the back of the shirt, and an attached auxiliary support cut and pressed from the top member overlying the shirt band opening, said auxiliary support being folded into the case in an upright position against the main support at the front of the collar band, said auxiliary support resting on the back of the shirt and together with the main support, supports the top member from the back of the shirt to prevent the collar from being crushed by pressure tending to flatten the case.

4. A substantially square sheet of foldable material forming an elongated case that is materially deeper at its upper end than at its lower end and

that has inwardly and upwardly converging sides, said sheet having a notch in each of its edge portions, the two notches at the upper end of the case being relatively shallow and the two notches at the lower end thereof being relatively deep, the edge portions of the shallow notches extending toward the intermediate corner of the sheet being in converging relation, a pair of parallel transverse scores extending between the corners of the shallow notches and between the outer ends of the converging edge portions thereof, a transverse score extending between the corners of the deep notch, a pair of converging longitudinal scores extending between the corners of the shallow notches and the corners of the deep notches, a pair of diverging longitudinal scores between said converging scores and extending between the upper transverse score and the corners of the deep notches, and a pair of short outwardly diverging scores between the two upper transverse scores and extending from the upper ends of the two diverging longitudinal scores and the outer ends of the outermost upper transverse score.

5. The structure defined in claim 4 further including a pair of short outwardly diverging scores between the first noted short scores at the innermost upper transverse score.

NEAL I. PAULSEN.
